UNITED STATES PATENT OFFICE

122,958

DESIGN FOR A SURFACING MACHINE

Richard F. Kneisley, Toledo, Ohio, assignor to
The American Floor Surfacing Machine Com-
pany, Toledo, Ohio, a corporation of Ohio

Application July 10, 1940, Serial No. 93,539

Term of patent 14 years

To all whom it may concern:

Be it known that I, Richard F. Kneisley, a citizen of the United States and resident of Toledo, county of Lucas, and State of Ohio, have invented a new, original, and ornamental Design for a Surfacing Machine, of which the following is a specification, reference being had to the accompanying drawing, forming a part thereof.

Figs. 1 and 2 are opposite side views of a sur-

facing machine showing my new design; Fig. 3 is a front perspective view thereof, and Fig. 4 is a rear end view of the machine.

The dominant features of my design reside in the solid line portions thereof.

I claim:

The ornamental design for a surfacing machine, substantially as shown and described.

RICHARD F. KNEISLEY.
